ATTORNEY

UNITED STATES PATENT OFFICE.

ALEXANDER TETI, OF TORRINGTON, CONNECTICUT.

BOOT.

Application filed May 14, 1923. Serial No. 638,956.

To all whom it may concern:

Be it known that I, ALEXANDER TETI, a citizen of Italy, residing at Torrington, in the county of Litchfield and State of Connecticut, have invented new and useful Improvements in Boots, of which the following is a specification.

The object of my said invention is the provision of a laced and buttoned boot constructed in such manner as to facilitate the entrance of the foot into the vamp portion of the boot and to enhance the dressy appearance of the boot when the same is completely fastened on the foot and about the leg.

To the attainment of the foregoing, the invention consists in the improvement as hereinafter described and definitely claimed.

In the accompanying drawings, forming part of this specification:—

Figure 1 is a view showing as open so much of a boot as is necessary to illustrate my invention.

Figure 2 is a similar view showing the said portion of the boot as buttoned and closed.

Figure 3 is a detail vertical section illustrating the arrangement of the tongue of the boot relative to the upper portion of the vamp and the lace employed to connect the eyelet carrying portions of the boot downward.

Figure 4 is a side elevation of the boot showing the same as completely buttoned and laced.

Similar numerals of reference designate corresponding parts in all of the views of the drawings.

My novel boot is designed by preference, though not necessarily, for use as a riding boot, and it includes a sole 1, a heel 2 and a vamp 3. The said vamp 3 is discontinued at one side of the longitudinal median line of the boot and at a point above the instep 45 of the boot as designated by 4. On the vamp and slightly in front of the said termination 4 are provided buttons 5, said buttons being by preference of the usual type used on shoes.

50 In addition to the vamp characterized as described the boot comprises a tongue 6, the lower end portion of which is arranged under the vamp adjacent to the said termination 4 and is appropriately connected to the said vamp. The boot also comprises leg portions 7 and 8 which are joined at the back

of the boot by a bight 9 and are provided with eyelets 10 and hooks 11 for the engagement of a lace 12. The leg portion 7 is merged into the vamp at the inner side of the boot as indicated by 13. The leg portion 8, however, is carried over the terminal portion 4 of the vamp somewhat after the manner of the "blucher" type of shoe and is connected at 14 to the sole 1. The said lapped part of the leg portion 8 is designated by 15, and is provided with a series of button holes 16 for cooperation with the buttons 5 in the ordinary well known manner.

Manifestly in putting on my novel boot, the boot is unbuttoned, and the lace is loosened sufficiently to permit of the easy insertion of the foot into the vamp portion of the boot. The boot is then buttoned and the lace is tightened and fastened when as will be readily apparent the boot will snugly fit the foot and will present a neat and dressy appearance. While the unbuttoning of the boot will contribute materially to the facility with which the foot may be sheathed in the vamp portion of the boot, the boot may be expeditiously and easily buttoned after application thereof when the buttons will contribute to the neat fit of the boot and at the same time will ornament the boot so that the same as a whole will present a neat and dressy appearance.

I have entered into a detailed description of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention various changes and modifications may be made such as fall within the scope of my invention as defined in my appended claim.

Having described my invention, what I claim and desire to secure by Letters Patent, is:—

A boot comprising a sole, a vamp attached to the sole and having a transverse termination at one side of the longitudinal median line of the boot and at a point above the instep of the boot, buttons on the vamp at one side of the longitudinal median line thereof and in front of and spaced relation to said termination, a leg portion merged into the

vamp at the inner side of the boot, a leg portion joined through a back bight to the first-named leg portion and having its forward lower portion lapped over the termination of the vamp and connected to the sole and provided with button holes for cooperation with the said buttons, a tongue con-

nected to the said termination of the vamp, and means for lacing the leg portions at the front of the portion of the boot above the 10 instep vamp portion thereof.

In testimony whereof I affix my signature.

ALEXANDER TETI.
